(57) **CLAIM**

The ornamental design for a sample rack adapter, as shown and described.

DESCRIPTION

FIG. 1 is a perspective view of a sample rack adapter showing my new design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a bottom perspective view thereof; and,

FIG. 9 is a perspective view of a sample rack adapter placed in a sample rack which is not part of the claimed design. The broken lines in the drawings depict environmental subject matter and form no part of the claimed design.
